TUFTING MACHINE

Murl A. White, Sumter, S. C., assignor to Polly Prentiss, Inc., Sumter, S. C., a corporation of South Carolina

Application February 23, 1938, Serial No. 192,097

3 Claims. (Cl. 112—79)

My invention relates to tufting machines.

An important object of the invention is to provide a machine of the above mentioned character, which is extremely simple in construction, 5 compact, and reliable in operation.

A further object of the invention is to provide means whereby the looper and cutter may be readily removed as a unit.

A further object of the invention is to provide 10 means whereby the cutter or blade is mounted separate from or independently of the looper, to have a shearing action therewith, the shearing action being effected by a relative movement between the looper and cutter.

A further object of the invention is to provide 15 means for mounting the cutter or blade separate from or independently of the looper, and to simultaneously turn the cutter and looper clockwise and then simultaneously turn them counterclockwise when viewed from the same side and effecting a relative movement between the cutter and looper.

A further object of the invention is to provide 20 means whereby the looper is moved by the cutter.

A further object of the invention is to provide 25 means to operate the cutter, which means is independent of the work feed means.

The present application is a continuation in 30 part of my co-pending application for Tufting machines, Serial No. 148,228, filed June 14, 1937.

Other objects and advantages of the invention will be apparent during the course of the following description.

In the accompanying drawings forming a part 35 of this application and in which like numerals are employed to designate like parts throughout the same,

Figure 1 is a side elevation of a tufting machine embodying my invention, parts in section, 40 and parts broken away.

Figure 2 is a front end elevation of the same, parts in section,

Figure 3 is a side elevation of the cutter and 45 looper and associated elements,

Figure 3a is a similar view, the looper moved toward the needle,

Figure 4 is a perspective view of the operating parts of the machine,

Figure 5 is a vertical view taken on line 5—5 of Figure 3,

Figure 6 is an exploded perspective view of the cutter, looper, and associated elements,

Figure 7 is a diagrammatic view showing the relative movements of the looper and blade, and,

Figure 8 is an edge elevation of a bell crank lever for operating the central rock shaft, associated elements being in side elevation, and parts in vertical section.

In the drawings wherein for the purpose of illustration is shown a preferred embodiment of my invention, the numeral 10 designates a sewing machine as a whole, of any well known or preferred type, such as the ordinary Singer sewing machine, comprising a stock 11, arm 12 and head 13. The stock is mounted upon a flat base 14. The head 13 is provided with the usual vertical reciprocatory needle bar 15 having a needle 16 clamped thereto. This needle has the usual eye at its lower pointed end for receiving the tufting 15 yarn or thread, passed through the usual guide and tension means, not shown.

The machine comprises the usual drive shaft 17, suitably journaled in the arm 12, and horizontally arranged, as shown, and driven by a 20 grooved pulley 18, which may be manually or power driven. At its forward end the drive shaft 17 is provided with a crank disc 19 rigidly secured thereto, and having pivotal connection with a link 20. This link is pivotally connected with a 25 sleeve 21, which is clamped to the needle bar 15. The machine further comprises a presser foot 22, of the usual construction, clamped to a presser bar 23, moved downwardly by the usual spring and raised by a finger engaging lever 24.

Arranged below the base 14 are horizontal rock shafts 25 and 26, which are held in suitable bearings. The sewing machine further comprises work feed means, to advance the work from the operator, including work feed dogs 27, operating 30 through a suitable opening in the base or through the throat plate, as is well known. These dogs are actuated by a rigid dog supporting bar or link 28, to which they are rigidly secured. At one end, the bar or link is rigidly connected with a 35 transverse head 29, which is pivotally connected with upstanding cranks 30, in turn rigidly mounted upon the rock shaft 25. At its opposite end the rigid bar or link 28 is provided with a fork 31, receiving a roller 32, pivotally mounted 40 upon a crank 33, in turn rigidly mounted upon the rock shaft 26. The rock shafts therefore serve as the operating means for the bar 28, serving to actuate the work feed means. These rock shafts extend longitudinally of the drive shaft 17 and 45 are parallel therewith. The rock shafts 25 and 26 are provided adjacent to the stock 11 with cranks 34 and 35 respectively. The cranks 34 and 35 are pivotally connected with connecting rods 36 and 37 respectively, which are actuated

by cams 38 and 39 respectively, in turn carried and driven by the drive shaft 17. It might be stated at this point that the rock shaft 25 serves to move the dog carrying bar or link 28 longitudinally, while the rock shaft 26 serves to raise and lower the same. The rock shaft 17 is also provided with a crank 40. The foregoing description is that of the ordinary Singer sewing machine.

10 Depending from the base 14 are lugs 41 and 42, within which is mounted an auxiliary rock shaft 43, arranged between the rock shafts 25 and 26, and parallel therewith. Rigidly connected with the rear end of the rock shaft 43 is a crank 44, having a block 45 pivotally connected therewith, and sliding in an elongated slot 46 of a bell crank lever 47. This bell crank lever is carried by a rock shaft 48, journaled in stationary bearings formed in the base 14. Pivotally connected 15 with the end of the bell crank lever 47, at 49, is a connecting rod 50, extending upwardly, for pivotal connection with the crank 40. It is thus seen that the rock shaft 43 is rocked by the continuous rotation of the drive shaft 17. At its 20 forward end, the rock shaft 43 is provided with a disc or wheel 50', carrying a crank pin 51, eccentric therewith. This crank pin operates beneath the dog bar 28 but does not contact therewith.

30 A support is provided for the cutter and looper, to be described, and this support is removable with the cutter and looper as a unit from the lug 41, to which it is attached. This support comprises a plate 52, Figure 6, having a horizontal flange 53, carrying a rib 54, which is separate from the lug 41. The plate 52 has elongated vertical slots 55, to receive set screws 56. While the plate 52 is shown as adjustable, for the purpose of raising and lowering the looper, yet the adjustability may be dispensed with and plates of different height used. Coacting with the plate 52 is a plate 57, having a horizontal flange 58, provided with elongated slots 59, receiving set screws 60, to engage within screw threaded openings 61. The plate 57 is adjustable longitudinally of the plate 52, but this adjustability is not essential, as plates of different lengths may be used.

50 The numeral 62 designates a looper as a whole, comprising an arm 63, provided at its upper end with a looper element 64, having a downturned end or hook 65. It is preferred to use the downturned end 65 but this may be omitted under certain conditions. The arm 63 has a recess 66 and the arm is provided at its lower end with a cylindrical opening 67, to receive a pin or stud 68, rigidly attached to the plate 57. This stud serves as a fixed pivot upon which the lower end of the looper 62 turns. The looper 55 slidably engages the flat face of the plate 57, and the looper is mounted to swing vertically in the direction of the feed of the work, and the looper element 64 has its free end facing in an opposite direction to the feeding movement of the work, and this looper element is adapted to move across the path of travel of the needle 16, when the needle is lowered, to receive the loop from the needle, and to hold the loop from pulling out of the fabric when the needle rises. The 60 plate 57 carries a fixed pivot element 69, which is free from connection with the looper 62 and does not support the looper, but operates within the recess or cut out portion 66 without contacting with the looper. The numeral 70 designates a blade or cutter, having an angularly dis-

posed cutting edge 71 near its top for shearing action with the looper element 64 preferably having a cutting edge 72. The cutting edge 71 rubs against the cutting edge 72. The blade or cutter 70 slidably contacts with the looper 62 5 and this blade or cutter is provided with an opening 73, pivotally receiving the pin or pivot 69. This pivot element constitutes the sole support of the blade or cutter 70 which is mounted separate from and independently of the looper 10 72. The looper 72 not only does not carry the blade or cutter 70, but the looper is reciprocated by the blade or cutter 70 and for this purpose the blade or cutter 70 is provided near its upper end with a pin or stud 74, rigidly attached to the 15 blade 70 and this pin or stud is pivotally mounted within an elongated vertical slot 75, formed in the upper portion of the looper and extending through the upper end thereof. It is thus seen that the blade or cutter 70 turns upon the pivot 20 69, while the looper 72 turns upon the pin or stud 68. Since the upper end of the blade or cutter 70 is nearer to the pin 69 than the upper end of the looper 62 is to the pin 68, and since the upper ends of the blade and looper are connected to move together, their upper ends move horizontally for the same distance, but due to the difference in the length of the radii of the swinging parts, the blade or cutter 70 will be inclined or angularly displaced to a greater extent than 30 the looper, whereby a relative angular movement is effected between the blade and looper, causing the cutting edge 71 of the blade to sever the loops upon the looper element 64. The looper 62 and cutter 70 are separately mounted, and the pivot 25 68 constitutes the sole support for the looper. If this pivot were removed, the looped would drop or work down from the pivoted cutter, since the pin 74 would pass out of the slot 75.

Means are provided to reciprocate the blade 40 or cutter 70, comprising an arm or crank 76, having a head 77. The head is provided with an opening 78 to pivotally receive the pin 69 and the head also has an opening 79 which is elongated and receives a set screw 80, engaging with in a screw-threaded opening 81 formed in the blade or cutter 70. The arm 76 has an elongated slot 82, to receive the crank pin 51. The arm or crank 76 may be angularly adjusted with respect to the blade or cutter 70, to regulate the 50 length of the stroke of the blade. The pivot element or pin 69 extends through the opening 78, as stated, and through a washer 83, having a cut out portion 84 to receive the head of the set screw 80. A nut 85 has screw-threaded engagement with the outer end of the pin 69 and is held against turning movement by a lock nut 86, and a spring 87 is arranged between the nut 85 and washer 83.

55 In view of the foregoing description it is thus seen that the looper 62 and the blade 70 and associated elements are all bodily mounted upon the support including the plate 52, and by removing the plate 52 from the lug 41, the support, looper and blade may be removed as a 65 unit.

The operation of the machine is as follows:

When the needle 16 is near its uppermost position, the crank pin 51 is raised and swings the arm or crank 76 counter-clockwise, as viewed 70 from the front in Figure 3. The crank therefore swings the blade or cutter 70 counter-clockwise and causes the looper to travel from the needle. Since the pivots of the blade and looper are eccentric, their upper ends swing in circular- 75

ly curved eccentric paths, and since the extent of horizontal movement is the same, the extent of angular displacement or movement of the blade 70 is greater than that of the looper, effecting a relative turning movement between the blade and looper and causing the blade to sever the loop or loops upon the looper 64, but leaving the last loop unsevered. In Figure 7, the looper 62 and blade 70 adjacent to the upper arm *a* of the bracket are retracted from the needle, while in this same figure, looper 62 and blade 70 adjacent to the lower arm *b* of the bracket have been shifted toward the needle, the arcs indicating the path of travel of the upper ends of the looper and blade. The extent of throw of the blade may be regulated by adjusting the crank 16 so that the last loop will not be cut. While it is preferred to move the blade so that it will not cut the last loop, the invention is not necessarily restricted to this operation. As the needle descends the crank pin 57 is traveling downwardly, and swings the arm or crank 70 clockwise, looking from the front in Figure 3a, and the crank 16 then swings blade 70 clockwise, which in turn 25 swings looper 62 clockwise, causing the looper to travel toward the needle. The looper continues to move toward the needle and moves across the path of travel of the needle by about the time the needle has reached or slightly passed its lowermost position and continues to move slightly toward the needle as the needle begins to ascend. The looper therefore receives the loop thereon as the needle rises, and as the needle approaches or reaches its uppermost position, the 30 looper moves from the needle. The cutting edge 71 of the blade 70 moves toward the looper element 64 as the blade and looper element move from the needle, to sever the loop or loops upon the looper, and the cutting edge 71 moves from 35 the looper element as the looper element moves toward the needle to provide a suitable space for the loop when the looper element enters the loop.

It is to be understood that the form of my invention herewith shown and described is to be taken as a preferred example of the same and that various changes in the shape, size, and arrangement of parts, may be resorted to without departing from the spirit of my invention or the scope of the subjoined claims.

Having thus described my invention, what I claim is:

1. In an attachment for use with parts of a

sewing machine including a needle and work feed means, said attachment comprising a fixed pivot, a blade mounted upon the fixed pivot, means to turn the blade upon its pivot, a looper having the blade coacting therewith and adapted to enter the loop produced by the needle, the looper having an elongated opening near its upper end, a pin secured to the upper portion of the blade and entering the elongated opening, the pin causing the movement of the blade to move the looper, the pin also shifting longitudinally of the looper within the elongated opening, a pivotal mounting for the looper separate from the blade and constituting the means for supporting the looper to the exclusion of the blade, the mounting holding the looper against perceptible movement upon its longitudinal axis.

2. In an attachment for use with parts of a sewing machine including a needle and work feed means, said attachment comprising a fixed pivot, 20 a blade mounted upon the fixed pivot, means to turn the blade upon its pivot, a looper having the blade coacting therewith and adapted to enter the loop produced by the blade, a sliding connection between the upper portions of the blade 25 and looper to permit of relative vertical movements between such upper portions, a pivotal mounting for the looper separate from the blade and constituting the sole supporting means for the looper, the mounting holding the looper 30 against perceptible movement upon its longitudinal axis, the blade serving to swing the looper.

3. In an attachment for use with parts of a sewing machine including a needle and work feed means, said attachment comprising a pivot 35 extending transversely of the line of work, a blade mounted upon the pivot, means connected with the blade to turn it upon its pivot, a reciprocatory looper for movement in the direction of the line of work and having the blade coacting therewith and adapted to enter the loop produced by the needle, an element secured to the blade and slidably engaging the looper and shiftable longitudinally of the looper and serving to cause the looper to be moved by the blade, a mounting 40 for the looper separate from the blade and constituting the sole supporting means for the looper, the mounting holding the looper against perceptible movement upon its longitudinal axis 45 with respect to the mounting.
